UNITED STATES PATENT OFFICE.

ARNOLD LUTSCHG, OF GREAT BEND, KANSAS.

SHOE-STITCHER ATTACHMENT.

Application filed May 18, 1927. Serial No. 192,199.

The invention relates to channelling devices for shoe stitching machines, and has for its object to provide a device of this character comprising a plate which may be easily and quickly attached to the bed plate of the machine below the presser foot and needle, and provided with a channelling knife which may be easily and quickly moved upwardly to channelling position ahead of the needle, whereby a channel will be cut in the shoe sole ahead of the needle during the stitching operation, thereby allowing the thread or stitching to be imbedded in the sole.

A further object is to provide the channel carrying plate with elongated recesses, one of which being below the needle for allowing the stitching operation and the other in alinement therewith, and in which the channelling knife is mounted, and which knife may be moved upwardly to operative position, or downwardly to inoperative position when desired.

A further object is to provide the under side of the knife carrying plate with a groove terminating at the rear side of the plate, and in which groove is rotatably mounted the knife shaft, which shaft terminates at its rear end in an angularly disposed arm having a limited spring action and adapted to spring over lugs carried by the rear side of the plate for holding the knife in operative or inoperative positions.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of a portion of a stitching machine, showing the device applied thereto.

Figure 2 is a front elevation of a portion of a stitching machine and the channelling device.

Figure 3 is a front perspective view of the plate and channelling device.

Figure 4 is a rear perspective view of the plate and channelling device.

Figure 5 is a vertical transverse sectional view taken on line 5—5 of Figure 2.

Referring to the drawing, the numeral 1 designates a portion of a conventional form

of shoe stitching machine and 2 the bed plate thereof, and on which is mounted the channel carrying plate 3, by means of screws which pass through the apertures 4 in the plate 3, however this may vary as desired according to the make and type of stitching machine to which the device is applied. In stitching machines as at present constructed, it is desirable to channel the sole in advance of the needle 6 so that the stitching will be imbedded in the sole where it will be protected, and to accomplish this result a vertically disposed channelling knife 7 is provided, and which knife may be of any shape or configuration, but is in the same longitudinal plane as the needle 6, and in advance of the needle, whereby as the sole is passed over the plate 3 under the presser foot 8 a channel will be formed therein in which the stitches will be imbedded. The channelling knife 7 is provided with a right angularly disposed shaft 9, which is rockably mounted in a channel 10, in the underside of the plate 3, therefore it will be seen that the knife and its shaft may be easily and quickly removed from the plate 3 for repair and replacement purposes. The rear end of the shaft 9 terminates in a right angularly disposed spring arm 11, in a horizontal plane and at a right angle to the knife 7, therefore it will be seen that when the arm 11 is moved to the position shown in Figure 4, under the lug 12, the knife 7 will be in raised operative position, and the arm will engage the upper side of the bed plate 2 as clearly shown in Figure 5, therefore it will be seen that as the shoe sole is passed under the presser foot 8, the channelling device or knife 7 will form a channel therein in advance of the stitching operation.

The channelling knife 7 extends upwardly through an elongated aperture 13 in the plate 3, which aperture is sufficiently long to allow the knife, when the arm 11 is moved one hundred and eighty degrees to a position under the lug 14, to be received in the aperture 13 and recess 15 in the bed plate 2. Disposed in alinement with the elongated aperture 13 is a needle receiving aperture 15, which allows the needle to work in the usual manner.

From the above it will be seen that a channelling device is provided for shoe stitching machines, which device is simple in construction, the parts reduced to a minimum, may be easily and quickly applied,

and one which may be manufactured at a small cost and applied to stitching machines without varying the construction thereof.

The invention having been set forth what is claimed as new and useful is:—

The combination with a stitching machine bed plate, a presser foot above said bed plate, a needle adjacent said presser foot and bed plate, of a channelling device, said device comprising a plate detachably connected to the bed plate, a shaft rotatably mounted in a channel in the underside of the plate, said plate having elongated aligned apertures in its outer end in alinement with the needle

and through one of which the needle works, 18 a knife carried by the shaft and disposed in the other elongated aperture, the other end of said shaft terminating at the rear side of the plate in a right angularly disposed arm 20 and lugs carried by the rear end of the plate at opposite sides of the shaft and under which the arm is received for holding the knife in operative or inoperative position as desired.

In testimony whereof I hereunto affix my signature.

ARNOLD LUTSCHG.
